ELECTRONIC VALVE FOR OPERATING ON
VERY SHORT WAVES

Robert Warnecke and Jean Bernier, Paris, France,
assignors to Compagnie Generale de Tele-
graphie Sans Fil, a corporation of France

Application May 21, 1947, Serial No. 749,468
In France September 19, 1942

Section 1, Public Law 690, August 8, 1946
Patent expires September 19, 1962

4 Claims. (Cl. 315—6)

1

This invention is relating to electronic valves operating on very short waves.

It is now well known that certain of the principal phenomena which in the case of ultra-short waves oppose an efficient functioning of the ordinary valves, are due to the fact that in these valves the high frequency control signal contributes in communicating to the electrons their kinetic energy.

In the valves known as "velocity modulation," the fundamental difficulties resulting from this process of control, reduction of the input impedance in particular, have been remedied by employing a high frequency signal only to cause the velocity of the electrons in movement to be varied periodically by a fraction generally slight, of its value; the modulation in intensity of the current conveyed by the beam being carried out later on, in a space called "space of collection," by a grouping of the electrons due simply to the effect of the differences of their individual velocities. Thus, the high frequency energy necessary for the control is very slight, whilst the kinetic energy of the electrons is taken primarily from the source of continuous potential serving to accelerate the electrons.

In spite of its great advantage with respect to the ordinary process of control used in triodes or other valves of the same nature, the foregoing method is not completely satisfactory since the most efficient electronic grouping which can be obtained by known means in valves known as velocity modulation valves, leads—under the best conditions of construction and regulation—to a theoretical output value systematically limited and well below 100%; in the case of a longitudinal velocity modulation transformed into a density modulation by "drift" of the electrons in a space free from a field, this extreme theoretical value is about 58%, it being understood that the efficiency constitutes the ratio of the high frequency energy given up by the beam to the collector to the energy spent in the source of continuous current potential serving to accelerate the electrons.

The present invention has for its object to improve considerably the efficiency of all valves which are based, in the main, on a periodically variable transit time of the electrons resulting from the action on the beam of an adequate system of control, such as velocity modulation valves with control by longitudinal action or by transverse action of a high frequency field.

This invention consists in a particular arrangement and novel design of the system of control

2

for amplifier valves; and at the same time of the system of control and of the collector system for auto-oscillator valves.

The characteristic element common to all valves of the type forming the object of the invention is a particular arrangement of the system of control. The improved design on which this arrangement is based is the simultaneous action of several high frequency fields of suitable form which will be determined hereafter in such manner that the electronic current wave resulting therefrom lends itself better to a considerable exchange of energy with the high frequency field, or the high frequency fields of the collector.

15 It can be proved that the fact that the transit time is sinusoidal but of the form

$$f(\phi) = (2k-1)\pi + 2 \sin \phi + \sin 2\phi$$

20 where ϕ is the output phase of the electrons from the control system, and k is a whole number, produces under the best adjustment conditions a gain in efficiency of 16%, whilst the form

$$f(\phi) = (2k-1)\pi + 2(\sin \phi + \frac{1}{2} \sin 2\phi + \frac{1}{3} \sin 3\phi)$$

only gives a supplementary gain of 1.4%. It can be shown that the gain made by adding harmonics of higher and higher order to the transit time is less and less although the maximum efficiency thus does tend towards 100% when approaching the ideal form

$$(2k-1)\pi + 2 \sum_{n=1}^{\infty} \frac{\sin n\phi}{n}$$

35 Actually, this form expresses the condition at which all the electrons issuing from the control system in the course of a period pass at the same time into the collector and this when its electric field is a retarding one and a maximum.

40 It will be easily understood that in order to obtain such optimum forms of the duration of travel of the electrons between the control system and the collector system, the disturbance of control must be a superposing of harmonic disturbance. If it were possible to produce in decimetric or centimetric waves potentials of a form freely capable of adjustment by means of external generators, it would consequently be

45 possible to improve the efficiency of the transit time generators which the invention has in view, at least when they are used as amplifiers, retroactive or otherwise, up to a value of approximately 100% and this without the use of any particular system of electrodes.

Such an improvement would constitute one embodiment of the present invention in its most general form and is expressly provided for by the invention. Nevertheless, in the absence of such means, in the present state of the art, particular arrangements of the control system will be described which constitute embodiments of the present invention and which particularly permit, according to one characteristic of the invention of making up of this ideal external generator by making us of energy which can be found, in particular in the interior of the valve, according to another characteristic of the invention.

There will now be described the particular arrangement of the electrodes of the system of control of the valves forming the object of the invention. The object of this arrangement is to permit an optimum disturbance or a disturbance close to the optimum disturbance or perturbation to be applied to the beam resulting from the preceding generalities by the simultaneous action of several harmonic high frequency fields.

The embodiment of my invention as described herein is illustrated in the accompanying drawing in which:

Figures 1a and 1b show, diagrammatically, and respectively the electrode arrangement for longitudinal and transverse action of the high frequency field on the beam;

Figure 2 shows diagrammatically a velocity modulated beam tube with longitudinal control and using a drift space;

Figure 2a is a fragmentary view showing a modification of Figure 2 wherein the adjacent cavity resonators are separated;

Figure 3 shows diagrammatically an electrode arrangement for a velocity modulated beam tube with transverse control;

Figure 4 shows diagrammatically an electrode arrangement for the collector of the beam tube operating in accordance with a characteristic of the present invention;

Figure 5 is a diagrammatic showing of a velocity modulated beam tube having control and collector systems in accordance with my invention and adapted to operate as a self-oscillator;

Figure 6 is a diagrammatic showing of a velocity modulated beam tube with longitudinal control and employing a deflector field; and

Figure 7 shows diagrammatically a velocity modulation valve with retarding field.

It is necessary to distinguish as to whether the velocity modulation valve is controlled by longitudinal action or by transverse action of the high frequency field on the beam.

(a) For valves controlled by longitudinal action, the system of electrodes is diagrammatically illustrated in Figure 1a. It is essentially composed of a series of metallic gratings A, B₁, B₂, B₃ . . . B_n of single or multiple meshes located on the path of the electronic beam issuing from the cathode K and disposed perpendicularly to the beam. For the convenience of the explanation but without many restrictions as to the scope of the present invention, it will be assumed that these gratings are flat, parallel, completely equipotential and ideally permeable to the electrons. According to the principle of the present invention, there are applied between these gratings sinusoidal horizontal potentials $u_1=U_1 \sin \omega t$, $u_2=U_2 \sin 2\omega t$, $u_n=U_n \sin n\omega t$ . . . having preferably small amplitudes U₁, U₂ . . . U_n with respect to the continuous current potential U₀ corresponding to the mean velocity v_0 of the electrons. Without being restrictive, it will be the

same between all the gratings, that is to say, that all the gratings will be raised to the continuous potential U₀.

(b) For valves controlled by transverse action, the system of electrodes is illustrated diagrammatically in Figure 1b. It is composed of several pairs of electrodes B₁, B₂, B₃ . . . B_n capable furthermore of being reduced to wires each pair being arranged axially of the beam. It is known that with this class of control it is the longitudinal component of the high frequency field occasioned by the deformation of the field lines at the edges of the electrodes which causes the modulation of longitudinal velocity necessary for the creation of a wave of utilizable current and that the frequency of this phenomenon is in general double the frequency of the high frequency field. Consequently, if ω is the pulsation of the field of the collector there will be obtained between the couples of deflection electrodes B₁, B₂ . . . B_n transverse high frequency fields of pulsation $\omega/2$, $2\omega/2$, $3\omega/2$ . . . which can be considered as created by potentials $u_1=U_1 \sin \omega/2t$, $u_2=U_2 \sin \omega t$ . . . of slight amplitudes with respect to U₀.

It is quite understood that the diagrams comprising Figures 1a and 1b do not restrict the scope of the present invention. Thus, the number of the electrodes and the order in which the high frequency potentials are applied may be different; the electrodes may be raised to different continuous current potentials, they may be separated by spaces free from high frequency fields as shown in Figure 2a and indicated theoretically in Figure 1a, several couples of electrodes may correspond to the same pulsation of the high frequency field; the electrodes of Figure 1b need not be parallel nor at the same level.

It will be evident to any person skilled in the art that by suitably regulating the amplitudes of the potentials U₁, U₂, U₃ . . . there may be found at the outlet of the control system a disturbance of velocity necessary for the transit time of the electrons which approaches the ideal law and consequently obtain a higher efficiency than that which is found with known valves employing a single oscillating electric field for the control. If, in particular, for valves with longitudinal control there is employed a system of three electrodes A, B₁, B₂ fed by two sinusoidal potentials $U_1 \sin \omega t$ and $U_2 \sin 2\omega t$, it will be possible to obtain for the ideal valve conceived according to the present invention a theoretical efficiency of approximately 73% and this according to what has been stated above, with a negligible high frequency control power.

One method of carrying the invention into effect will now be described with reference to Figure 2, wherein a velocity modulation valve with longitudinal control employing a system of electrodes in which the transformation of the velocity modulation into density modulation is obtained by drift of the beam in a space free from electric field.

Like most of the examples hereinafter described, the valve has oscillating circuits comprising resonant spaces of revolution about the axis of the electron beam, having a profile of retracted form and known as "rhumbatron," but it is to be clearly understood that this particular type of oscillating circuit is only given by way of example and can be applied to transit time valves for very short waves, the associated oscillating

circuits of which comprise other systems such as sections of transmission lines or wave guides.

In Figure 2, an emissive cathode K is shown as heated by a filament F; in front of the cathode K are placed three gratings or grids A, B₁ and B₂. A and B₁ are incorporated in the walls of a rhumbatron R₁; B₁ and B₂ in the walls of a rhumbatron R₂. The rhumbatrons R₁ and R₂ are illustrated with a common wall but this particular arrangement is not obligatory and in no way restrictive, as the rhumbatrons R₁ and R₂ may be separated by a space in which, for example, there is no field. A Faraday cage t formed for example by a metallic tube electrically connects the gratings B₂ and M. M and N and M_N and N_N are the electrodes between which the electric field acts which is developed in the energy collector formed by a rhumbatron R₃ and others that may be used. With the arrangement illustrated in Figure 2, A, B₁, B₂, M and N are raised to a constant potential U₀. P is an electrode which collects the electrons after their passage in the collector due to a positive polarisation U_P which is regulated to a value just sufficient to collect them all. The rhumbatrons R₁ and R₂ are designed and adjusted in such manner as to have reciprocally self-oscillation pulsations equal to 2 ω and ω , ω being the vibration pulsation of the rhumbatron R₃.

If R₁ and R₂ are excited with alternating potentials of pulsations 2 ω and ω and of suitable phase so that the fields acting longitudinally of the beam have slight amplitudes but in the ratio of approximately 1 to 2 according to the elementary theory developed above, and if, the distance B₂M is judiciously chosen to correspond to the potentials according to the said theory, then the duration of transit of the electrons between B₂ and M is given by the equation hereinabove stated and the efficiency of such a valve will be approximately 73%. This result assumes that the effects of the space charge and of the transit time of the electrons in the collector are negligible, but it will be seen that the efficiency is much higher than that of usual velocity modulation valves where the system of control only comprises a field of pulsation ω and the maximum efficiency of which upon the same hypotheses, is 58%.

As has already been described, the valve illustrated in Figure 2 supplying energy on the pulsation ω requires two control potentials, one at the pulsation ω and the other as the pulsation 2 ω . As has been explained above, these two potentials may be chosen very small by providing a suitable construction and the corresponding high frequency powers may then be very small as compared with that which appears in the collector. A fraction of the latter appearing negligible at first, may thus be taken from the collector R₃ and delivered in correct phase into the rhumbatron R₂ to furnish the excitation at the pulsation ω . This may be produced by means of the coupling line l shown dotted, connecting the loops b₂ and b₃ located respectively in the rhumbatrons R₂ and R₃ (where they surround a magnetic flux). The valve obtained may then be considered as a retroactive amplifier which, excited by an independent high frequency source of pulsation 2 ω supplies energy at the pulsation ω . This useful energy may be, as is well known, transmitted to the utilisation load by a line l₄ connected to a loop b₄ which is located in the collector.

There will now be briefly described by way of

a second example, a velocity modulation valve with transverse control, provided with a device according to one of the principal characteristics of the invention.

In this example (Figure 3) the oscillating circuits (L₁B₁) (L₂B₂) and C are formed of sections of a transmission line, K is the cathode, P the electrode collecting the electrons (at a potential U_P>0, with respect to K just sufficient to collect all the electrons), D is a diaphragm serving at the same time as a focalising lens, B₁B₂ are the two pairs of electrodes of the control system, G₁G₂ the grids limiting the high frequency field of the collector C; D, B₁, B₂, G₁, G₂ are at the same continuous current potential U₀.

L₁ is the quarter wave element of the transmission line which, connected to the pair of electrodes B₁ forms an oscillating circuit of pulsation $\omega/2$.

L₂ is the quarter wave element of the transmission line which, connected to the pair of electrodes B₂, forms an oscillating circuit of pulsation ω .

L'3L''3 are elements of the transmission line which form with G₁G₂ an oscillating system of pulsation ω .

b₁ is the coupling loop of L₁ with the source S of pulsation $\omega/2$, and is connected to the latter by the line l₁.

b₃ is the coupling loop of L'3 with the utilisation circuit l₃ and

b₂ is the coupling loop of L₂ with the source of pulsation ω .

L₂ can be excited by means of a small part of the energy of the collector connecting b₂ by a line l to a loop b'3 placed in the vicinity of L'3. The valve can then be considered as a regenerative amplifier which, excited by an independent high frequency source of pulsation $\omega/2$, delivers energy at the pulsation ω .

Regulation takes place by acting on the coupling loops b₁, b₂, b₃, b'3, as also on l₁ and l.

In order to convert, according to the principle of the present invention, the valve with longitudinal control of Figure 2, into an autonomous auto-oscillator, there may be employed an energy collector forming the object of the second principle characteristic of the present invention.

This collector is arranged in such manner that it causes several high frequency electric fields (more or less limited) oscillating with pulsations ω , 2 ω , 3 ω . . . to act on the beam which passes through it.

It is composed essentially (Figure 4) of a set of metallic gratings M, N₁, N₂ . . . N_n which are similar to the gratings A, B₁, B₂ . . . B_n serving as elements to the system of control of Figure 1a and are arranged in the same way as those with respect to the beam. M and N₁ are incorporated or connected in a resonant oscillating circuit on a pulsation ω , N₁ and N₂ in an oscillating circuit of pulsation 2 ω , etc. . . . (it will be here noted that it is not necessary for the high frequency fields of pulsation ω , 2 ω , . . . to succeed in this order or be juxtaposed along the beam; they may for example be separated by spaces free from fields).

The operation and regulation of this collector of energy are based on the following observations:

As appears from the generalities at the outset, the maximum efficiency is obtained when the valve is regulated in such manner that the greater part of the electrons (if not the whole) issuing from the system of control in the course of a period, pass at the same instant through the col-

lector. The collector is thus excited by impulses of pulsation ω . On the other hand, it is well known that impulses of pulsation ω permit oscillatory system of pulsation $n\omega$ to be excited. It will thus be easily understood that by acting for example on the shunt impedances of the various oscillatory circuits of the above collector it is possible so to arrange that practically the whole of the energy transported by the beam appears in the resonant circuit of pulsation ω , whilst there appear in the oscillating circuit of pulsation 2ω , 3ω . . . only the energies just sufficient suitably to excite the system of control according to the invention. The valve having to act as a generator for a certain frequency corresponding to ω , it is useless and even injurious for an amount of energy greater than that which is necessary for the control to be taken from the beam and appear in the circuits tuned to 2ω , 3ω .

Referring to Figures 5, 6, and 7, there will now be described by way of examples, various modifications according to the present invention of auto-oscillator transit time valves provided with systems of control and with collectors arranged as described.

The valve illustrated diagrammatically in Figure 5 is a velocity modulation valve and with drift conversion in a space free from field. It is provided with only the control electrodes A, B_1 and B_2 and outlet electrodes M, N_1 and N_2 ; that is to say, that for the control and the taking of energy, only two fields in each case are caused to act, in accordance with what has been stated above these two fields which are juxtaposed resonating on ω and 2ω .

The rhumbatrons R_1 and R_4 are regulated to resonate on 2ω .

The rhumbatrons R_2 and R_3 are regulated to resonate on ω .

To obtain the maximum efficiency of the valve, the shunt impedance of R_3 is adjusted so that $U=U_0$ and R_4 is adjusted to a value just sufficient to enable the energy necessary to excite R_1 to be taken from the auxiliary collector so as to produce between A and B_1 the oscillating field with pulsation 2ω .

The transfer of energy between the corresponding rhumbatrons will take place for example through the lines l_1 and l_2 and magnetic coupling loops $b'1b''1$, $b'2b''2$.

The energy which can be employed at the pulsation ω will be transmitted to the load by a line l_3 and the loop b_3 located in the principal collector of energy R_3 .

Figure 6 illustrates diagrammatically a velocity modulation valve by longitudinal control and with deflector field. The control and collector systems as also the coupling systems are similar to those of the preceding valve.

The rhumbatrons $R_1R_2R_3$ and R_4 are raised to the same continuous current potentials U_0 ; P at the potential $U_p > 0$ is the electrode collecting electrons and H at the continuous current potential U_H is the deflecting electrode.

Figure 7 illustrates diagrammatically a velocity modulation valve with retarding field; the grouping of the electrons is effected by total reflection and the system of control operates at the same time as a collector of energy. This is composed essentially of two rhumbatrons R_1 and R_2 of pulsation 2ω and raised to the continuous potential U_0 ; P is the reflecting electrode, raised to a negative potential with respect to the cathode K. The electrons coming from K, are modulated in velocity by the system R_1R_2

grouped in the space R_2P and traversing afresh the system R_1R_2 where they give up their energy. The adjustments of the valve must be such that the energy given up is effected almost solely to the advantage of the electromagnetic field of R_2 , whilst there is produced in R_1 only a slight exchange of energy between the electrons returning and the electrons passing out.

It is known that valves with retarding fields and with sinusoidal control have a maximum theoretical efficiency lower than that of drift space valves. This is due principally to the restrictions of phase and of non-reflection of the electrons by the high frequency field, which do not exist in drift space valves. If, owing to the addition, according to the present invention, of several high frequency fields, it is possible to improve the grouping of the electrons and to be left free to a certain extent of the restriction of phase, the restriction of non-reflection of the electrons by the high frequency field still persists. The latter results in that U'/U_0 is at the most of the order of 0.70 instead of 1, and thus the maximum efficiency is of the order of 50% instead of 73%.

The invention is naturally capable of other modifications without departing from the spirit of the invention.

What we claim is:

30. 1. Electron beam tube comprising, a composite input resonator for producing a periodic velocity variation of the electrons and constituted by at least two side-by-side elementary resonators each comprising a group of two grids between which there is connected a resonant circuit, means connected to said input resonator providing a drift space for causing the velocity modulated electron beam to form into bunches while traversing this space, and an output resonator connected to said means for receiving the radio frequency energy of the bunched electron beam comprising a resonant circuit tuned to a fundamental frequency with means for connection to a utilization circuit, the resonant fundamental frequencies of said elementary resonators being chosen respectively equal to the said fundamental frequency and harmonics thereof, where n is the number of elementary resonators.

50. 2. Electron beam tube according to claim 1, in which any two of the successive elementary resonators comprise a common grid.

55. 3. Electron beam tube according to claim 1, in which the output resonator is in the form of a group of elementary resonators of which the number and the electrical characteristics are similar to those of the input resonator, and coupling means between the elementary resonators the frequencies of which correspond to each other in the input and output resonators, whereby the tube behaves as a generator of waves at the fundamental frequency.

60. 4. An electron beam tube according to claim 1, in which the output resonator is in the form of a group of elementary resonators of electrical characteristics similar to those of the input resonator, each of the elementary resonators of the input resonator being coupled with a corresponding elementary resonator of the output resonator, with the exception of one at least thereof, from among those of which the resonant frequency is an harmonic of said fundamental frequency, and means comprising a sinusoidal voltage source outside the tube and coupling means between said source and said last mentioned res-

onator for externally exciting it by said harmonic frequency.
